[57] CLAIM

The ornamental design for a loose fill packing material, as shown and described.

DESCRIPTION

FIG. 1 is an isometric view of one embodiment of a loose fill packing material showing our new design;
 FIG. 2 is a front elevational view thereof;
 FIG. 3 is a right side elevational view thereof;
 FIG. 4 is a rear elevational view thereof;
 FIG. 5 is a top view thereof; and,
 FIG. 6 is a bottom plan view thereof.
 The left side is a mirror image of the right side.
